HIGH-VOLTAGE SPARKER FOR SELF-SUPPORTING CABLE WITH BARE MESSENGER

Edward K. Duffy, Rome, N. Y., assignor to Rome Cable Corporation, Rome, N. Y., a corporation of New York

Application February 9, 1951, Serial No. 210,256

6 Claims. (Cl. 175—183)

1

This invention relates to method and apparatus for testing self-supporting type cable for insulation faults. This type of cable comprises one or more insulated conductors twisted about a central uninsulated conductor which acts as a supporting messenger. It has been impossible to spark test this type cable during manufacture with the apparatus heretofore available because a bare messenger in passing through the sparker apparatus heretofore available would immediately ground any applied voltage.

Accordingly it is an object of this invention to provide method and apparatus for spark testing self-supporting type cable.

Another object of the invention is to provide spark testing apparatus through which cable of the self-supporting type may be continuously passed without disturbing the twist or lay of the insulated conductors.

Another object of the invention is to provide means for insulating the bare messenger of self-supporting type cable while impressing a high voltage on insulated conductor means twisted around said messenger.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a perspective view of an embodiment of the device;

Figure 2 is a vertical cross section taken on the line 2—2 of Figure 1;

Figure 3 is a vertical cross section taken on the line 3—3 of Figure 1;

Figure 4 is an enlarged longitudinal cross section of the left hand end of Figure 1; and

Figure 5 is a diagrammatic plan view.

In the embodiment of the invention shown herein a length of self-supporting type cable 10, comprising, an uninsulated conductor or messenger 10^a, and the insulated conductors 10^b and 10^c respectively spiralled around said uninsulated conductor or messenger 10^a, is shown extending between a pay-off stand or reel 12 (Figure 5) and the take-up stand or reel 14, the ends of said

2

cable being grounded at said reels respectively, as indicated at 16 and 18.

An assembly, comprising an insulating tube 20 and the annular collars or end disks 22 and 24 fitting over the ends respectively of tube 20, is mounted between the pillow blocks 26 and 28 in which respectively the end disks 22 and 24 of said assembly are received and rotatably supported. The pillow blocks are connected to ground as indicated in Figure 5 at 30 and 32. The annular end disks 22 and 24 have the laterally extending flanges 22^a and 24^a respectively through which set screws 34 extend to fasten said end disks on the tube. The ends of the tube are flush with the outer ends of said end disks and the uninsulated conductor 10^a is led in a straight line directly through the tube. Between the center opening of said end disks 22 and 24 through which tube 20 extends and the outer periphery 10 of said end disks respectively pairs of holes 36 and 37, and 38 and 39 respectively are disposed side by side and extending parallel to the tube so that both insulated conductor 10^b which is led through holes 36 and 38 successively and conductor 10^c which is led through holes 37 and 39 successively, extend over and around the exterior surface of tube 20.

Preferably the pillow blocks 26 and 28 are spaced apart a distance equal to the lay of the cable so that each of said insulated conductors 10^b and 10^c make one complete turn around the exterior surface of insulating tube 20 in passing between said end disks 22 and 24. It will thus be seen that as the cable 10 is advanced the spiral winding of the conductors 10^b and 10^c will cause the assembly of the insulating tube 20 and the end disks 22 and 24 to revolve in accordance with the lay of the cable. If it is desired to test cables of different lay one end disk may be loosened, by loosening its set screw 34, and angularly revolved relative to the other end disk as much as is required.

Surrounding said insulating tube 20 are one or more rings 40 of conductive material. Either a number of narrow rings spaced apart as shown, or a single continuous tubular member may be employed. The assembly of insulating tube 20 and end disks 22 and 24 and the insulating rings 40 surrounding tube 20 intermediate the guide plates, extends in close proximity to a high voltage electrode. As shown herein this assembly extends through an electrode 42 which is tubular in form when closed and comprises two semi-circular portions 42^a and 42^b hinged together by the hinges h, the portion 42^a being supported on

the insulating standards 43 and the portion 42^b having a number of chains 44 extending across it transversely and connected at their ends along the respective longitudinal margins of said electrode part. The chains 44 are long enough to form loops hanging down into the interior of the electrode and yieldingly contacting and extending partly around the surface of the portions of the insulated conductors 10^b and 10^c passing through said electrode, and also contacting the conductive ring or rings 48. High voltage is supplied to the electrode through lead 46 from any suitable source, and it will be understood that this high voltage is transmitted to said ring or rings 48 through contact between said ring or rings and one or more of said chains 44. The insulated conductors 10^b and 10^c, in passing through the electrode and travelling over and around insulating tube 28, pass over conducting ring or rings 40 and between said ring or rings and the chains 44 of the electrode device. Thus high voltage is impressed by the chains 44 on and around a more or less semi-circular portion of the insulation of said conductors 10^b and 10^c, and high voltage is impressed upon a portion of the surface of said conductors 10^b and 10^c opposite to said semi-circular portion by contact with said conducting ring or rings 40. Thus the high voltage is impressed substantially over the entire insulation surface of the conductors 10^b and 10^c and any faults in the insulation cause sparking i. e. bridging of the distance between a high voltage contact (chains 44 or ring or rings 40) and the core of the conductor, which may be detected and recorded in a well known manner.

By the method disclosed herein self-supporting type cable may, for the first time, be spark tested. The apparatus disclosed herein provides preferred means for carrying out the method, which is novel and fills a long existing need.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

What I claim is:

1. Apparatus for spark testing the insulation of the insulated conductors of a self-supporting cable having an uninsulated conductor and one or more insulated conductors wound spirally around said uninsulated conductor, without untwisting the insulated conductor or conductors, which comprises, a pair of rotatable guide means each having a central aperture of a size to receive said uninsulated conductor, and one or more other apertures radially related to said central aperture, and of a size to receive said one or more insulated conductors, said guide means being positioned in spaced relation with their said central apertures in alignment, and support means for said guide means respectively, an insulating tube positioned between said guide means and aligned axially with the said central apertures of said guide means, an electrode having yielding contact members extending into close proximity with the said external surface of said insulating tube, and means to continually advance said cable,

whereby said uninsulated conductor may be continuously passed through the central aperture in said guides and through said insulating tube, and said one or more insulated conductors may be continuously passed through the said other apertures of said guide means respectively, over and spirally around the external surface of said insulating tube and into contact with the said yielding contact members of said electrode.

2. Apparatus for spark testing the insulation of the insulated conductors of a self-supporting cable having an uninsulated conductor and one or more insulated conductors wound spirally around said uninsulated conductor, without untwisting the insulated conductor or conductors, which comprises, a pair of rotatable guide means each having a central aperture through which said uninsulated conductor may be passed and one or more other apertures radially related to said central aperture, through which said one or more insulated conductors may be passed, said guide means being positioned in spaced relation with their said central apertures in alignment, and support means for said guide means respectively, an insulating tube positioned between and rotatable with said guide means and aligned axially with the said central apertures of said guide means, an electrode having yielding contact members extending into close contact with the said external surface of said insulating tube, and means to continually advance said cable, said insulating tube having on its external surface a conductive area in contact with the said yielding contact members of said electrode.

3. The method of testing a cable comprising one or more insulated conductors wound spirally around and supported by a bare messenger which comprises, supporting the insulated conductor or conductors by passing them individually through a plurality of spaced apart, aligned, rotatable support means, continuously advancing said cable through said support means and employing the twist of said insulated conductor or conductors to rotate said support means, interposing insulating shield means between said insulated conductor or conductors and said bare messenger during the travel of said cable between said support means, and subjecting the insulated conductor or conductors to a spark test while separated from the bare messenger by said insulating shield means.

4. The method of testing a cable comprising one or more insulated conductors twisted around and supported by a bare messenger without untwisting the cable which comprises, continuously advancing the cable and throughout a portion of its travel separating the insulated conductor or conductors from the bare messenger while rotating the cable in accordance with the lay of said insulated conductor or conductors by passing the insulated conductor or conductors and the bare messenger individually through spaced and rotatable support means, interposing an insulating member between said insulated conductor or conductors and said bare messenger and rotating said insulating member in accordance with the lay of said insulated conductor or conductors, and subjecting the insulated conductor or conductors to a spark test while separated from the bare messenger by said insulating member.

5. Apparatus for locating faults in the insulation of a cable comprising one or more insulated conductors spiralled around a bare messenger which comprises, an insulating tube and rotatable guide means for said insulated conductors positioned respectively to direct said bare messen-

ger through said insulating tube and said insulated conductor or conductors over the external surface of said tube, and grounded means for supporting and advancing the cable continuously whereby said rotatable guide means will be rotated by said insulated conductor or conductors according to the twist of said conductor or conductors, an electrode including means for contacting the surface of said insulated conductor or conductors while they are passing over said insulating tube, and a connection between said electrode and a high power source.

6. The apparatus claimed in claim 5 in which said insulating tube is also rotatable and means are provided for rotating it in synchronism with the rotation of said rotatable guide means.

EDWARD K. DUFFY.
